(57) **CLAIM**

The ornamental design for a light fixture, as shown and described.

DESCRIPTION

FIG. 1 is a perspective view of a light fixture.

FIG. 2 is a left side view of the light fixture of FIG. 1.

FIG. 3 is a right side view of the light fixture of FIG. 1.

FIG. 4 is a front end view of the light fixture of FIG. 1.

FIG. 5 is a rear end view of the light fixture of FIG. 1; and, FIG. 6 is a bottom view of the light fixture of FIG. 1.

Portions or features of the light fixture not shown in the drawings form no part of the claimed design. The broken lines in the drawings form no part of the claimed design.
